United States Patent Office.

CALVIN H. FARNHAM, OF CANTERBURY, CONNECTICUT.

Letters Patent No 91,731, dated June 22, 1869.

IMPROVEMENT IN FEATHER-RENOVATORS.

The Schedule referred to in these Letters Patent and making part of the same.

To all whom it may concern:

Be it known that I, CALVIN H. FARNHAM, of Canterbury, Windham county, State of Connecticut, have invented certain new and useful Improvements in Feather-Renovators; and I do hereby declare that the following is a full and exact description thereof, reference being had to the accompanying drawings, and to the letters of reference marked thereon.

In the drawings—

Figure 1 is a cross sectional view,

Figure 2, a plan view, and

Figure 3, a side view of my device.

The object of my improvements is to perfect the drying-cylinder of a feather-renovating machine, whereby the same is rendered quicker in operation and more thorough in its work, as well as being more easily handled.

In my improved device, I use a double-walled lower portion in the cylinder, which enables the same to be thoroughly heated by steam or hot air, without the condensing of the same moistening the inside of the cylinder, where the feathers are placed, thereby allowing them to be dried perfectly.

I also arrange the arms for stirring the feathers in a peculiar manner around the main rotating shaft, enabling the same to be turned much more easily, as well as preventing any drip from the condensing of the vapor after steaming the feathers directly.

And by peculiar devices used upon the drying-cylinder I am enabled to pack the feathers, after steaming and drying, into the tick or case, as may be, by merely turning the main shaft.

In fig. 1 it is shown that the jacket A extends inside of the cylinder B, covering the three lower octagonal sides entirely, leaving a space, C, between, for the hot air or steam to fill.

The main conducting-pipe D branches into two pipes, E and E', outside of the cylinder, at the end, (see fig. 3,) the branch-pipes E and E' extending between the walls, nearly to the other end of the cylinder, thus tending to heat it more evenly.

Secondary branches, F, are arranged so as to extend upwards on each side from the pipes E and E', and these pipes, F, are made much smaller, and serve to conduct the steam throughout the space C more entirely and evenly than would otherwise be the case.

Braces, G, are placed between the walls at intervals, to prevent the jacket from collapsing or blowing out under the shifting-pressures occasioned by alternately introducing the steam in the main cylinder and in the space C, for the purpose of first steaming the feathers and afterwards drying them.

The main shaft H is hollow, as is also shown in O. T. Pennell's patent renovator, patented —, and the stirring-arms a a a are hollow, and connect with the inside of the shaft H, through which the steam is conducted in cleaning the feathers.

In the peculiar arrangement of these arms, in connection with the hollow cylindrical shaft H, I obtain

a great advantage, as well as in the construction of the arms themselves.

It will be seen in the fig. 1 that the arms a, a, a, &c., are arranged upon the shaft H so as to form a spiral dasher.

This arrangement accomplishes the following purposes:

First, in enabling the shaft to be turned more evenly and easily, by equalizing the strain, only one arm coming against the densest mass of feathers at a time, this being at the point nearest to the botto, where the feathers would naturally settle when sodden with the steam used in cleaning them.

Second, in stirring the feathers more perfectly, and not lifting them up in one mass and dumping them over again, as is the case when the arms a, a, a, &c., are ranged in straight lines.

And in this effect also is included the more perfectly forcing the feathers into the tick or case, through openings made for the purpose.

These openings consist of traps, J and K, the one, J, made for ticks, being at the front lower side, and the one, K, for pillow-cases, bolsters, &c., being placed at the end.

These and their construction will hereafter be more fully described.

At the bottom of the main cylinder is a trap, M, which, when open, leaves only a sifting-plate, O, to keep the feathers in the cylinder.

This sifter allows the dust and worms to be thoroughly sifted out of the feathers before steaming.

The traps K and J are provided with hooks, p p, &c., around their openings, through which the feathers are driven, as before described.

The hooks p p, &c., serve to attach the bolster or tick in place.

The arms a a, &c., are provided with flanges, e e, &c., which greatly assist in beating the dust out of the feathers.

The advantages of these improvements are great, as the feathers are dusted, steamed, and dried perfectly, in their transit through the machine, and finally packed back into the tick without waste in filling.

Now, having described my invention,

What I claim as new, and desire to secure by Letters Patent, is—

1. The arrangement of the arms a a a, with flanges e e e, in a spiral around the main cylinder H, substantially as shown and described.

2. In combination with the drying-cylinder, constructed as described, the jacket A, with sifter O, at the bottom, when used in connection with the pipes E and E', with branch pipes F F, &c.

3. The construction of the traps J and K, with hooks p p, &c., around their openings, substantially as and for the purpose shown.

Witnesses: CALVIN H. FARNHAM.
